UNITED STATES PATENT OFFICE.

HERBERT A. JONES, OF HIMRODS, NEW YORK.

CATTLE-MARKING TOOL.

SPECIFICATION forming part of Letters Patent No. 748,613, dated January 5, 1904.

Application filed April 14, 1903. Serial No. 152,630. (No model.)

To all whom it may concern:

Be it known that I, HERBERT A. JONES, a citizen of the United States, and a resident of Himrods, in the county of Yates and State of New York, have invented certain new and useful Improvements in Cattle-Marking Tools, of which the following is a specification.

This invention relates to a cattle-marking tool, and has for its object to provide a simple handy tool for indelibly marking the bodies of cattle with figures, letters, or other marks of identification.

The peculiar advantages and novel features of the tool will be hereinafter pointed out in the specification and claims.

In the drawings, Figure 1 represents a top view of the tool. Fig. 2 is a side elevation. Fig. 3 is an end view, and Fig. 4 is a cross-section on the lines 4-4 of Fig. 1.

It is often desirable and convenient for purposes of registration and in other cases where means of identification are important to stamp or tattoo cattle and other animals upon the inside of the ear, where such marking can be made and will show. This is accomplished by me by a tool in the nature of a pair of pliers provided with a lever carrying at their jaws means for adjustably holding type-blocks or dies and inking-ribbon upon rollers.

The pliers are represented in the drawings as comprising the arms A' A², pivoted together at their ends, as at A³, and normally held apart by the spring A⁴. Plates B B are attached on each side of one of the arms A², as by screws b. The other arm A' is free to move up and down between the said plates B. A lever C is pivoted between said plates B, as by the screw b', so that when the lower cam-shaped end C' of said lever C is forced down upon said arm A' by elevating the lever C, the jaws of the arms A' A² are closed. When pressure is removed from the lever C, the spring A⁴ opens them.

The upper arm A' carries a platen D, which is represented as fastened to said arm by a transverse slot in its upper side which receives the end of said arm and a threaded bolt a, that passes through said arm and into said platen. A rubber block d may be introduced into said groove in said platen D beneath the arm A', so that said platen may be firmly attached to said arm by the bolt a, and

yet a certain amount of adjustment is possible by compressing said rubber block.

The lower arm A² of the pliers carries the type-supporting block E, which is secured to the end of said arm A² in a manner similar to that described above with reference to the platen D—that is to say, the end of the said arm A² lies in a transverse slot in said block E and is secured therein by a screw-bolt e. A case F, that holds the ink-rollers G and G', is also supported upon the end of the arm A² by means of said bolt e. A rubber block H is introduced between the case F and the type-block E in order to secure a firm connection between the end of said arm A² and said block E and at the same time permit adjustment of said parts in the manner in which the platen may be adjusted upon the other arm A'. Any other compressible material may be used for the blocks d and H. The type-block E is adapted to receive and retain the die. The drawings represent the block E as having undereut edges e', that are adapted to engage a similarly-shaped type-plate I, and the bolt e is adapted to lock said type-plate I by engaging its under surface, as shown in Fig. 4. The rollers G and G' are represented as mounted upon axes g g', respectively, that pass transversely through said frame F on either side of the arms of the pliers. Knobs g² and g³ are attached, respectively, to the ends of said axes, by which the rolls can be turned to wind the ribbon I' upon one of said rolls from the other. The ribbon I' passes from one roll up over the type-plate I and down to the other roll. The ribbon is saturated or coated with a suitable ink for indelibly marking hides and is moved along the top plate I as often as a fresh piece of ribbon is required. This affords a very handy and effective means of keeping the type well inked for use at all times. The inked ribbon can be readily and quickly replaced by a fresh roll by unscrewing the knobs G² G³ and then withdrawing the axes g g', having first removed the casing F by taking out the screw-bolt e. The long leverage obtained by pivoting the arms at these extremities, the means shown and described above for adjustably securing the platen and type-block to the arms A' A², respectively, and the use of a cam for bringing the said arms

together produce a tool with which a deep impression can be made with the application of slight force and also an impression that will be uniform throughout the entire type-plate.

5 Other means besides the lever C may be employed for turning the cam C' for the purpose of closing the jaws of the pliers.

By adjusting the platen D upon the arm A' and the type-block E upon the arm A² the pliers can be set so that they will make a depression of the proper depth every time that the cam C' is rotated to its full depth whatever force may be applied to the lever C or other means that are employed to actuate the 15 cam.

What I claim is—

1. In a cattle-marking tool the combination with two arms pivotally connected together, of a platen; means for yieldingly attaching said platen to one of said arms; a die upon the other arm, said platen and die being adapted to engage with each other when the ends of said arms are close together; means for vertically adjusting said platen and said die upon said arm, respectively; means for closing the ends of said arms; and a spring tending normally to separate said arms.

2. In a cattle-marking tool the combination with two arms pivotally connected together, of a platen; means for yieldingly attaching said platen to one of said arms; a die; means for yieldingly supporting said die upon the other of said arms; means whereby said arms are caused to approach within a fixed distance of each other; and means for adjusting either the platen or die upon its support with reference to the other said part.

3. In a cattle-marking tool the combination

with two arms pivotally connected together at one end, of the platen D upon the free end 40 of one of said arms; the adjustable bolt d; a compressible block between said arm and said platen; and a die upon the opposite arm, substantially as shown and described.

4. In a cattle-marking tool the combination 45 with two arms pivotally connected together at one end, of the die-block E upon one of said arms; the adjustable bolt e; a compressible block between said arm and said die; and a platen upon the other said arm; substantially as shown and described.

5. In a cattle-marking tool the combination with two arms pivotally connected together at one end, of the platen D upon the end of one of said arms; the adjustable bolt d; a 55 compressible block between said arm and said platen; the die-block E upon the opposite arm; the adjustable bolt e; and a compressible block between said arm and said die-block, substantially as shown and de- 60 scribed.

6. In a cattle-marking tool the combination with two arms pivotally connected together, of means for closing the free ends of said arms; a platen upon the end of one of said arms; a die-supporting block upon the end of the other of said arms; the easing F; the axes g g' supported within said casing; the inking-rolls G G' upon said axes; and means for transferring the ribbon from one roll to the 70 other across the die, substantially as shown and described.

HERBERT A. JONES.
